UNITED STATES PATENT OFFICE.

MORRIS W. POOL, OF NEW YORK, N. Y., ASSIGNOR TO UNION TYPEWRITER COMPANY, OF JERSEY CITY, NEW JERSEY, A CORPORATION OF NEW JERSEY.

TYPE-WRITING MACHINE.

No. 899,615.

Specification of Letters Patent. Patented Sept. 29, 1908.

Application filed October 16, 1905. Serial No. 283,015.

To all whom it may concern:

Be it known that I, MORRIS W. POOL, citizen of the United States, and resident of the borough of Brooklyn, city of New York, in the county of Kings and State of New York, have invented certain new and useful Improvements in Type-Writing Machines, of which the following is a specification.

My invention relates to the tabulating mechanism of typewriting machines, and more especially to that class of tabulating mechanisms which employ a denomination stop member or members in coöperation with a plurality of column stops.

The main object of my invention is the provision of means to enable a key when operated to cause a denomination stop member and any selected one of the plurality of column stops to be brought into position for coöperation with each other, so that, when such coöperation is brought about, any selected denomination position in any selected column will be brought to the printing position.

So far as I am aware it is new in the art to provide a denomination stop and a plurality of column stops which are adapted at a single operation to be brought into relation for coöperation between said denomination stop and any selected column stop so that a predetermined denominational position in a predetermined column may be obtained when the carriage is released, and this whether the denomination stop is one of a plurality of such stops, as shown herein, or a single denomination stop variably movable to different denominational positions, as shown in my companion application filed of even date herewith, Serial No. 283,016. It is also new to move the movable member from normal to coöperative position by a single means. The results herein attained in one operation by a single key-actuated means have heretofore required two or more operations or a plurality of key actuated means, as shown, for example, in the patent to Schlesinger and Young, No. 714,523, dated Nov. 25, 1902.

My invention consists in certain features of construction and combinations and arrangements of parts, which will be fully set forth herein and particularly pointed out in the claims.

I have shown my invention as applied to a type-writing machine resembling generally

the No. 6 Remington typewriter and to a tabulating mechanism generally resembling that commercially known as the Gorin tabulator. In the devices illustrated, a plurality of column stops are employed which are mounted upon the movable paper carriage of the machine and are independently adjustable lengthwise thereof, although, having been properly adjusted for the work in hand, said column stops are maintained in a fixed relation during the operation of the machine. These column stops coöperate with a plurality of denomination stops which are shown in the form of separate blade-like members arranged side by side and mounted on a fixed part, said denomination stops being independently movable by their associate denomination keys into position to coöperate with the column stops. Each denomination key is also adapted to cause a release of the paper carriage to bring about a coaction between the column stops and the denomination stop associated with said denomination key.

My invention is applicable to various kinds of writing machines and tabulating devices, but in the present instance I prefer to embody said invention in the particular styles of mechanisms illustrated in the accompanying drawings, in which,—

Figure 1 is a fragmentary top plan view of a type-writing machine and a tabulating mechanism embodying my invention, various parts being omitted. Fig. 2 is a central longitudinal sectional view of the machine and the associated tabulating devices, parts of the machine being omitted. Figs. 3 and 4 are detail views showing parts of my invention. Figs. 5, 6, and 7 are enlarged fragmentary sectional views showing a tabulator key in various positions along with its forward bearing and associated parts. Fig. 8 is an enlarged fragmentary perspective view of the scales or indicators associated with two of the tabulator keys.

First considering more especially Figs. 1 and 2, 1 indicates the base of the machine supporting corner posts 2, which latter sustain a top plate 3. A series of type bar hangers are circularly arranged on the top plate, each hanger 4 pivotally supporting a type bar 5 which is connected by a link 6 with a printing key lever 7 fulcrumed at 8 in the rear of the base and provided with a restoring spring 9. The type bars are adapted

to coöperate with the under side of a paper support or platen 10 mounted in a platen carrier 11 which in turn is pivotally connected by links 12 with a carriage truck 13. The 5 platen carriage comprising the carrier 11 and truck 13 is provided with rollers 14 and 15 which coöperate with front and back guide rails 16 and 17 respectively to support and guide the carriage as it is moved from side to 10 side of the machine. A feed rack 18 is secured to arms 19 pivoted at 20 in the carriage truck and said feed rack normally meshes with a feed pinion 21 fixed to the front end of a shaft 22 which has its bearings 15 in a bracket 23 secured to the top plate by screws 24. An escapement wheel 25 is mounted on the rear end of the shaft 22, and adapted to coöperate with said escapement wheel are feed dogs 26 mounted at the top of 20 a pivoted dog rocker 27. Secured to the dog rocker are forwardly extending arms 28 which are connected by hook-like members 29 with a universal bar 30 which extends from side to side of the machine beneath the 25 series of key levers 7. When any key lever is actuated to operate the printing mechanism, the universal bar is thereby actuated, causing the dogs 26 to coöperate in a known manner with the escapement wheel 25 to permit the carriage to be drawn a letter space distance in printing direction under the influence of a spring drum 31 with which the carriage is connected by a band 32.

A rack bar 33 extends parallel with the 35 carriage truck and is adjustably secured by screws 34 to the rear ends of arms 35 extending rearwardly from brackets 36 which fit over or embrace the carriage truck 13 and are removably and adjustably secured thereto by screws 37. The front and rear faces of the rack bar 33 are formed with teeth 33^a a letter space distance apart and the top of the rack bar is preferably provided with a scale corresponding to the ordinary carriage and 40 platen scales of the machine. The rack 33 is adapted to receive one or more column stops, four of such stops being shown in the drawings and marked respectively 38, 39, 40 and 45 41. Each of the column stops may be formed of a flat piece of metal cut away to embrace the rack bar 33 and to fit in between the teeth 33^a of said rack bar. The column stops generally resemble each other in construction, but differ in respect to the extent 50 to which they extend rearwardly from the rack bar 33. As will be noted from a consideration of Figs. 1 and 2, the stops from left to right extend rearwardly progressively increasing distances, or, in other words, comprise a series of stepped stops, the stop 38 having its contact portion extending rearwardly to a less extent than the stop 39, which in turn extends rearwardly to a less degree or extent than the stop 40, the said 55 stop 40 extending rearwardly to a less extent

than the stop 41. By this construction the contact points of the plurality of column stops are provided, whose contact points are out of line and in different planes of travel. It will be understood that the number of column stops used will depend upon the character of the tabulating work in hand, and that a less or greater number of stops may be employed than are shown. In certain aspects of my invention the column stop member may be regarded as comprising the column stop rack bar and the column stops thereon.

A vertically arranged frame or bracket 42 is clamped to the rear of the base of the machine and to the top plate by set screws 43. The bracket 42 is provided with rearwardly extending ears 44 which support a fulcrum rod 45. Pivoted on the fulcrum rod 45 are a series of vertically disposed levers 46, each lever being bifurcated at the top to embrace a pin 47 carried by a denomination stop 48. The denomination stops 48 are here shown in the form of blade-like members slidably mounted on roller bearings 49 carried by 50 bearing rods 50 which are supported in side walls 42^a formed at the top of the bracket 42. Eight denomination stops are shown in the drawings arranged side by side a letter space distance apart and confined between 55 the side walls 42^a of the bracket 42. In certain aspects of the invention the denomination stop member may be regarded as comprising the set of blades or stops 48.

The lower ends of the levers 46 are shouldered away at the bottom to form depending lugs 46^a and each of said lugs is surrounded or embraced by the perforated rear end of a tabulator push rod 51, said push rods forming a series which fans outwardly towards 100 the front of the machine after passing through bearings in a cross web 42^b formed integral with the bracket 42 and extending beneath the rear edge of the base of the machine. The forward end of each push rod 51 is provided with a finger button or key 52, the front surface 52^a whereof and the top surface 52^b whereof are both adapted to be 105 pressed by the fingers of the operator. The general appearance of the key 52 is best 110 shown in Fig. 8 of the drawings.

A short distance in rear of its key cap or button 52, each push rod 51 has its under surface provided with a plurality of notches or recesses, four of such notches being shown in the drawings and numbered respectively 115 from front to rear 53, 54, 55 and 56. Slightly to the rear of the last notch 56 each push rod 51 passes through a perforation in a collar-like member 57. The under part of the 120 bearing in the collar 57 is formed into a tooth-like portion 58 which is shaped to conform to the series of notches 53 to 56 inclusive. The rod 51 normally contacts with the tooth 58 in the collar 57 just to the rear of 125

the last notch 56. A spring member 59 supports the collar 57 and has its forward portion bifurcated (Figs. 3 and 4), the arms 59^a of the bifurcation extending forwardly and downwardly and embracing the push rod 51, the ends of the arms being secured to the rear face of the collar 57 at either side of the opening in said collar by headed screws 60. The rear end of the spring supporting member 59 is perforated to receive a headed screw 61 which screws in a supporting frame 62 and secures the spring member 59 thereto. It will be understood that each of the push rods 51 is provided with a bearing collar 57 and that each bearing collar is connected by a spring 59 with the supporting frame 62. The frame 62 extends from side to side of the machine, beneath the forward part of the base 1 and is formed with a longitudinal groove 63 which receives the bottom part of the front end 1^a of said base. The frame of support 62 is provided with lugs 64 in rear of the part 1^a of the base, said lugs receiving screws 65 which abut against the rear face of the part 1^a and serve to secure the support 62 fixedly to said base. A small right-angled bracket 66 is secured by a screw 67 to the bottom of the support 62 so that the downwardly extending arm of said bracket is close to the rear face of the collar 57. The downwardly extending arm of the bracket 66 is formed with a perforation 68 which normally registers with a recess or depression 69 (Fig. 6) in the collar 57. A pin 70 is fixed in the top of the push rod 51 in rear of the bracket 66 and the upper part of said pin is bent forwardly and horizontally and normally passes through the hole 68 in the bracket 66 and into the depression 69 in the collar 57. With the pin 70 in the position just described the associate collar 57 is maintained against the support 62 and cannot be moved or depressed away from said support.

Forward of the base of the machine the support 62 has secured to it a scale plate or member 71, which, as herein shown, extends longitudinally of the support 62 and comprises a portion 71^a sloping forwardly and downwardly from the front of the base, a vertically disposed portion 71^b bent downwardly from the part 71^a, a second downwardly and forwardly sloping portion 71^c, and a second vertically disposed portion 71^d. The sloping portion 71^a is provided with a denominational scale, that is to say, above each of the denomination keys 52 the face of the part 71^a is marked with the corresponding denomination, whether units, tens, hundreds or the like. The ordinary system of notation is used in the drawings and reads from left to right: .1 10 100, etc., up to 1,000,000, which last relates to the eighth or right-hand key. As best shown in Fig. 8, the portion 71^d is cut away as indicated at 71^e so as normally to half surround the push rods

51, and at one side of each of the cutaways 71^e and adjacent to the associate push rod 51 the scale plate 71 is provided with a forwardly projecting and horizontally disposed lip or tab 71^f. The top surface of each lip 70 or tab is preferably stamped or otherwise marked with the letters "Col" (meaning column) or with some equivalent indicating column mark. An arrow is preferably stamped on the face 71^d just above each mark "Col", 75 said arrow pointing to the top of the cutaway or opening 71^e. Forward of the opening 71^e the top of each push rod 51 is stamped or otherwise provided with a plurality of bands or stripes 72, four of such bands or stripes 80 being shown on each rod associated with the stamped numerals, "1", "2", "3" and "4", the numeral 1 being associated with the forward band or stripe 72 and the other numerals successively with the second, third and 85 fourth bands or indicating marks 72. The numerals "1", "2", "3" and "4" correspond to the notches 53, 54, 55 and 56, respectively, the construction being such that when the rod 51 is pushed in until one of said 90 numerals registers with the plate 71, the corresponding notch stands over the tooth 58 in the collar or ring 57. By off-setting the portions of the member or scale plate 71 in the manner described, I am enabled to separate 95 the denominational scale far enough from the column indicating devices of said scale to avoid confusing the operator, while at the same time providing a convenient device which combines the functions of a denominational scale and a column indicator. 100

In order to effect a release of the carriage by any of the tabulator keys, I provide a universal bar 73 that lies under all of the rods 51. Said universal bar is mounted on the 105 forward ends of side arms 74, the rear ends of said side arms being secured to a rock shaft 75 which has its bearings in the sides of the base 1 of the machine. Fixed to the rock shaft 75 near its middle is a rearwardly projecting arm 76 (Fig. 2), the free end of which is connected at 77 with an upwardly extending link 78 which passes through a hole in the top plate of the machine and is pivotally connected at 79 with an L-shaped 110 lifting member 80, said lifting member 80 being pivoted at 81 to the side of the escape- 115 ment bracket 23. The member 80 extends forwardly beneath the carriage feed rack 18 and is then bent longitudinally of said rack, as indicated at 82 (Fig. 1), the bent portion 82 being provided at either side of the feed pinion 21 with lifting shoes 83 which normally stand below the teeth of the rack 18 and are adapted, when the member 80 is raised, to engage said rack and lift it out of engagement with said pinion. The link 78 is provided with a lug 78^a which is adapted to engage the under side of the top plate and limit the upward movement of said link. 120 125 130

Each push rod is surrounded by a helical restoring spring 84. The forward end of the spring 84 is secured to a lug 85 depending from a bar 86 which is fastened by screws 87 to the base of the machine, and the rear end of the spring is fixed to a collar 88 which is secured to the rod 51 by a screw 89.

The operation of the mechanism above described will now be explained.

- 10 Suppose that the operator be engaged in making up a tabular statement, that in such statement there are to be four columns running up and down the sheet in about the relative positions indicated by the column stops 15 38, 39, 40 and 41 in Fig. 1, and that a line has been partly written so that the carriage has moved about thirty-five spaces from left to right so that it is in about the position shown in Fig. 1. If then it be desired to write a 20 certain amount, say \$500, in the third column, the operator will press rearwardly on the face 52^a of the fourth tabulating key 52 from the left, which is the "hundred" key as may be seen by the denomination scale on 25 the face 71^a of the scale plate 71. The "hundreds" key is pressed rearwardly until the edge of the opening 71^c in the scale plate registers with that stripe or band 72 marked "3", indicating the third column. The parts 30 will now be in the position shown in Fig. 6 and from an inspection of said figure it will be observed that the rod 51 has been moved longitudinally towards the rear until the notch 55 in its under side, which is the notch 35 corresponding to the third column position, is in register with the tooth 58 in the bearing collar 57. It will further be observed that the bent pin 70 has been withdrawn from engagement with both the perforation 68 and 40 the recess 69. The rearward longitudinal movement of the rod 51 serves to swing the lower arm of its associate lever 46 rearwardly about the fulcrum 45 and to swing the upward arm of said lever forwardly. The 45 forward movement of the upper arm of the lever acts on the pin of the associate denomination stop 48, sliding said stop forwardly on the rollers 49. The parts are so proportioned and adjusted that when the "hundreds" key has been pressed rearwardly to the position indicated in Fig. 6 with the third column band "3" in register with the edge of the scale plate, then the corresponding denomination stop 48 (in this case the fourth or 50 "hundreds" stop) will have been slid forward far enough, as indicated by the dotted lines in Fig. 1, to coact with the third column stop 40 when the carriage is released. As 55 soon as the edge of the opening 71^c registers 60 with the desired indicating mark 72, the operator presses down on the surface 52^b of the key 52, thereby swinging the forward end of the rod 51 downwardly about its bearing in the web 42^b as a fulcrum. The downward

movement of the rod 51 causes the notch 55 to engage with the tooth 58 which serves to thereafter prevent longitudinal movement of the rod 51 in either direction. During the continued downward swinging movement of the rod 51 the collar 57 moves with it, the associate spring 59 yielding to permit such movement. As the rod 51 begins to swing downwardly it acts upon the release bar 73, rocking the shaft 75 and swinging the arm 76 upwardly, thereby causing the link 78 to swing the lifting member 80 upward about its fulcrum 81. The upward movement of the member 80 brings the shoes 83 into engagement with the carriage feed rack 18 and causes them to swing the rack upwardly about its pivots 20 until it is disengaged from the feed pinion 21. As soon as this disengagement takes place the carriage is free to be drawn leftward across the machine by the spring drum 31. This free movement or "jump" of the carriage will continue until the third column stop 40 engages with the projected denomination stop 48, which stop it will be noted from an inspection of Fig. 1 has not been projected far enough forward to 90 engage either the first column stop 38 or the second column stop 39, so that both said stops 38 and 39 are skipped and neither serves to interrupt the "jump" or free movement of the carriage. The releasing position 95 of the push rod 51 and the parts associated therewith near its forward end are indicated in Fig. 7 of the drawings. The parts are so proportioned and adjusted that the disengagement between the carriage rack and pinion does not occur until the proper notch 100 in the under side of the rod 51 has engaged with the tooth in the positioning and bearing collar 57, the result being that the projected denomination stop has been arrested in the desired predetermined position before the release of the carriage occurs.

When the actuated denomination key 52 is released the spring 59 serves to restore the collar 57 to normal position, said collar as it moves upward carrying with it the push rod 51 which at the same time is pulled longitudinally forward by its restoring spring 84, the tooth 58 and the notches with which said tooth engages being so formed as to permit 115 of the longitudinal return movement of said rod 51. As soon as the actuated key 52 is released the rack 18 is restored by its spring (not shown) to engagement with the pinion 21 and the releasing devices, comprising the 120 lifting member 80, link 78, arm 76, arms 74 and bar 73, are restored to normal position by gravity. The desired number, *i. e.*, 500, may then be written in the third column by manipulating the printing keys in the usual 125 manner.

The operation above outlined may be repeated with any of the denomination keys

- and it will be understood that each and all of said keys may be actuated to cause at a single operation a variable projection of their associate denomination stops from normal position in order to position said stops to engage with any desired one of the plurality or set of column stops; and to skip or pass any column stops which may be between the projected denomination stop and the desired 5 column stop. While care must be exercised in properly positioning the actuated tabulating key in order to project its associate stop to engage with the selected column stop, it will, nevertheless, be observed (more especially from consideration of Figs. 5 and 6) that there is a considerable range of movement of the push rod 51, longitudinally considered, within each one of what may be called the column fields. Consequently the 10 bands or stripes 72 representing the column fields may be comparatively broad, and it is only necessary to register any part of the desired mark or band 72 with the opening in the scale plate in order to properly project 15 the desired denomination stop, and this registering or coöperation between the marks 72^b and the scale plate may be done quite rapidly in the practical operation of the machine.
- While, considered from certain aspects, it 20 is not necessary in carrying out my invention to combine in one operation both the positioning of the coöoperative denomination and column stop member for coöperation and the releasing of the carriage in order to bring 25 about such coöperation, it is, nevertheless, preferable in practice to so combine the positioning and releasing operations in order to conserve time. The method of combining the positioning and releasing operations 30 which has already been described and explained is efficacious and comparatively simple. The operator preferably actuates the desired denomination key 52 with the thumb in contact with the face 52^a of said key and 35 the forefinger in contact with the top face 52^b of said key. Pressure is exerted against the key by the thumb until the desired column mark 72 is in register with the edge of the opening in the plate 71 and thereupon pressure is partly transferred from the thumb to 40 the forefinger which serves to swing the push rod 51 downwardly so as to fix the position of the projected denomination stop and to release the carriage, the whole movement of 45 the key 52 being performed in a single and continuous operation. The key, it will be observed, is movable in two directions, a rearward direction and a downward direction, and the extent of these movements varies, the extent of the downward rotary 50 movement of the key depending on the extent to which it has first been pushed rearwardly towards the fulcrum in the bearing web 42^b. The release is always operated at
- the last part of the downward movement of 65 the key whatever the extent of such movement.
- Various changes may be made in the arrangement, construction and disposition of the mechanism described, and parts of it may be employed without other parts, all without departing from the spirit and scope of the invention.
- What I claim as new and desire to secure by Letters Patent, is:—
1. In a typewriting machine and in tabulating mechanism, the combination of a carriage, column determining stops, key operated denominational positioning devices co-operating with said column determining stops, and means for variably operating said denominational positioning devices to select a column.
  2. In a typewriting machine and in tabulating mechanism, the combination of a carriage, a set of column stops having contact surfaces out of line with one another, denominational positioning mechanism, and means for variably operating said denominational positioning mechanism to move a part of said denominational positioning mechanism into line with any selected one of said contact surfaces.
  3. In a typewriting machine, the combination with a carriage, of a series of column stops, and denominational stop mechanism for coöperation with said column stops to arrest the carriage in selected denominational positions, said mechanism including a denominational stop and means for moving said denominational stop to any one of a plurality of predetermined operative positions to select the column.
  4. In a typewriting machine, the combination with a carriage, of a series of column stops, denominational stop mechanism for coöperation with said column stops to arrest the carriage in selected denominational positions, said mechanism including a denominational stop, and key controlled means for moving said denominational stop to any one of a plurality of predetermined operative positions to select the column and for releasing the carriage.
  5. In a typewriting machine, the combination with a carriage, of tabulating mechanism comprising a set of stops having contact surfaces out of line with one another, a second set of separately operable stops, and means for moving any one of said separately operable stops to different operative positions for coöperation with any one of said contact surfaces.
  6. In a typewriting machine, the combination with a carriage, of tabulating mechanism comprising a set of stops having contact surfaces out of line with one another, a second set of separately operable stops, means

for moving any one of said separately operable stops to different operative positions for coöperation with any one of said contact surfaces, and a carriage releasing device operative by said stop-moving means.

7. In a typewriting machine, the combination with a carriage, of tabulating mechanism comprising a series of column stops having contact surfaces out of line with one another, a series of separately operable denomination stops, and means for moving any one of said denomination stops into position to coöperate with any one of said contact surfaces.

10. In a typewriting machine, the combination with a carriage, of tabulating mechanism comprising a series of column stops having contact surfaces out of line with one another, a series of separately operable denomination stops, means for moving any one of said denomination stops into position to coöperate with any one of said contact surfaces, and carriage releasing means operative by said stop-moving means.

8. In a typewriting machine, the combination with a carriage, of tabulating mechanism comprising a series of column stops having contact surfaces out of line with one another, a series of separately operable denomination stops, means for moving any one of said denomination stops into position to coöperate with any one of said contact surfaces, and carriage releasing means operative by said stop-moving means.

9. In a typewriting machine, the combination with a carriage, of tabulating mechanism comprising two sets of stops, the stops of one set having contact surfaces out of line with one another, and each stop of the other set being separately movable to different positions for coöperation with said contact surfaces, keys for effecting such movements of said stops, and carriage releasing means operated by said keys.

10. In a typewriting machine, the combination with a carriage, of tabulating mechanism comprising a series of column stops having contact surfaces out of line with one another, a series of denomination stops, each separately movable different distances to bring it into position for coöperation with the different contact surfaces, a series of keys, one for each of said denomination stops, a carriage release device operated by any of said keys, and means preventing the operation of said carriage release device by a key until the corresponding denomination stop has been moved to operative position.

11. In a typewriting machine, the combination of a series of separately operable denomination stops, a coöperative stop, and means for moving any one of said denomination stops from normal position to any one of a plurality of operative positions for coöperation with said coöperative stop.

12. In a typewriting machine and in a tabulating mechanism, the combination of a plurality of column stops varying progressively in length; a plurality of denomination stops arranged a letter space distance apart; and key actuated means for moving any of said denomination stops to any one of a plurality of positions to coöperate with any selected column stop.

13. In a typewriting machine and in a tabulating mechanism, the combination of a plu-

rality of column stops varying progressively in length; a plurality of denomination stops arranged a letter space distance apart; and key actuated means for moving any of said denomination stops to any one of a plurality of positions to cause it to coöperate with any selected one of said column stops and for releasing said carriage to effect such coöperation between said selected stops.

14. In a typewriting machine, the combination with the paper support and with the printing mechanism, one of said parts being movable with respect to the other, and with an escapement and propelling means for said movable part, of means for arresting the travel of said movable part embracing two members, one of said members comprising a plurality of column stops mounted on one of said parts and the other of said members comprising a plurality of denomination stops and being mounted on the other of said parts, the stops of one of said members being each separately movable to position to engage the other stops; a series of keys arranged to variably actuate said movable stops, the construction and arrangement being such that such varying actuations effect engagements of predetermined column stops and predetermined denomination stops; and key actuated means for releasing the carriage from the escapement mechanism.

15. In a typewriting machine, the combination with the paper support and with the printing mechanism, one of said parts being movable with respect to the other in the direction of the line of print, of means for arresting the travel of said movable part embracing two members, one of said members comprising a plurality of column stops mounted on one of said parts and the other of said members comprising a plurality of denomination stops mounted on the other of said parts, the stops of one of said members being each separately movable; and means for actuating said movable stops to position to effect the engagement of a predetermined column stop and a predetermined denomination stop.

16. In a typewriting machine, the combination with the paper support and with the printing mechanism, one of said parts being movable and provided with an escapement and propelling means, of a plurality of column stops mounted upon one of said parts; a plurality of separately movable denomination stops mounted on the other of said parts; a plurality of finger keys adapted to move said denomination stops variably, the construction and arrangement being such that such variable actuations effect engagements between the denominational stops and predetermined column stops when said movable part is released; and means actuated by said plurality of finger keys for releasing said movable part from its escapement.

17. In a tabulating mechanism for typewriting machines, the combination of a plurality of column stops having their contact points out of line, a plurality of variably movable denomination stops; and key actuated mechanism for imparting variable movements to each of said denomination stops whereby any one of said stops may be brought into position to engage any predetermined one of said column stops. 5
18. In a tabulating mechanism for typewriting machines, the combination with the paper carriage, of a plurality of independently adjustable column stops having their contact faces arranged in progressive vertical planes; a horizontally movable denomination stop member adapted to engage said column stops; and key mechanism for moving said denomination stop member from 15 normal position to any one of a plurality of predetermined positions to cause it to engage any selected one of said column stops. 20
19. In a tabulating mechanism for typewriting machines, the combination with the paper carriage, of a plurality of independently adjustable column stops having their contact faces arranged in progressive vertical planes; a plurality of horizontally movable denomination stops, each adapted to engage 25 said column stops; and key mechanism for moving each of said denomination stops from normal position to any one of a plurality of predetermined positions to cause them to engage any selected one of said column stops. 30
20. In a typewriting machine and in a tabulating mechanism, the combination of a carriage; a plurality of column stops thereon; a plurality of denomination stops, each variably movable to coöperate with selected column stops; means for variably moving said denomination stops; and means on said last recited means to indicate the extent to which said denomination stops are moved. 35
21. In a typewriting machine and in a tabulating mechanism, the combination of a carriage; a plurality of column stops thereon; a plurality of denomination stops, each variably movable to coöperate with selected column stops; means for variably moving said denomination stops, said means comprising push rods; and a scale for each of said push rods to indicate the extent to which it has been actuated to variably move its associate denomination stop. 45
22. In a typewriting machine and in a tabulating mechanism, the combination of a series of column stops; a series of denomination stops; means including a plurality of keys movable to variable extents to bring 50 selected column stops and selected denomination stops into coöoperative relation; and a combined denomination indicator and column indicator associated with said keys. 55
23. In a typewriting machine and in a tabulating mechanism, the combination of a se- 60 ries of column stops; a series of denomination stops; means including a plurality of key actuated push rods movable to variable extents to bring selected column stops and selected denomination stops into coöoperative relation, said push rods being provided with column indicating devices; and a denomination scale associated with said push rods, said scale being provided with column indicating devices coöoperative with the column indicating devices on said push rods. 70
24. In a typewriting machine and in a tabulating mechanism, the combination of a series of column stops; a series of denomination stops; means including a plurality of key actuated push rods movable to variable extents to bring selected column stops and selected denomination stops into coöoperative relation, and denomination and column indicating devices for said push rods. 80
25. In a typewriting machine and in a tabulating mechanism, the combination of a series of column stops; a series of denomination stops; means including a plurality of key actuated push rods movable to variable extents to bring said column stops and said denomination stops into coöoperative relation, said push rods each being provided with a column scale; and a denomination scale plate fixed to the frame of the machine 90 and associated with said push rods, said scale plate being provided with indicating portions coöoperative with the column scales on said push rods. 95
26. In a typewriting machine and in a tabulating mechanism, the combination of a carriage; tabulating stops adapted to be brought into coöoperative relation; and key actuated means for effecting relative movements of said stops so as to bring two of them into coöoperative relation so as to arrest the carriage in any desired columnar position and any desired denominational position within the desired column at a single operation. 100
27. In a typewriting machine and in a tabulating mechanism, the combination of a set of column stops having variably extending engaging portions, a set of denomination stops, and means for moving each denomination stop different predetermined distances so as to engage and coöperate with any of said column stops. 110
28. In a typewriting machine and in a tabulating mechanism, the combination of a member comprising a plurality of column stops having variably extending engaging faces, a denomination stop member, and means for variably moving one of said members at a single operation into position for co-operation between said denomination member and any selected column stop. 120
29. In a typewriting machine and in a tabulating mechanism, the combination of a series of column stops having contact surfaces out 125

- of line with one another, a coöperating stop, means for effecting a relative adjustment between said series of column stops and said co-
operating stop comprising a key movable in
5 two directions and connections adapted to
effect such adjustment by a motion in one
direction, and means in position to be oper-
ated by said key when moving in another
direction for releasing the carriage.
- 10 30. In a typewriting machine and in tabu-
lating mechanism, the combination with a
carriage, of a series of column stops having
contact surfaces out of line with one another,
a series of denomination stops each movable
15 different distances to bring it into line with
the contact surface of one or another of said
column stops, keys, each movable in two di-
rections, and connections for operating said
denomination stops when said keys are
20 moved in one direction, a universal bar in po-
sition to be operated by any of said keys
when moved in another direction, and a car-
riage release device operated by said uni-
versal bar.
- 25 31. In a typewriting machine and in tabu-
lating mechanism, the combination with a
carriage and tabulating stops, of a push rod
for moving one of said tabulating stops to
30 different positions, said push rod having a
notched part and a device which coöperates
with the notches to position the push rod ac-
curately.
32. In a typewriting machine and in tabu-
lating mechanism, the combination with a
35 carriage, of column stops having stop sur-
faces out of line with one another, a series of
denomination stops each movable different
distances to bring it into line with one or an-
other of said stop surfaces, a series of push
40 rods for operating said denomination stops
by a longitudinal motion of said push rods, a
universal bar lying beneath said push rods in
position to be operated by a depression of one
of said push rods, and a carriage release de-
vice operated by said universal bar.
- 45 33. In a typewriting machine and in a
tabulating mechanism, the combination of a
plurality of column stops, a plurality of sepa-
rately operable denomination stops, and
key actuated means for moving any selected 50
denomination stop from normal position into
anyone of a plurality of positions to coöper-
ate with any selected column stop.
34. In a tabulating mechanism for type-
writing machines, the combination with a 55
plurality of independently adjustable column
stops having contact points out of line, of
means adapted at will to engage and arrest
any predetermined one of said column stops,
said means comprising a plurality of sepa- 60
rately operable denomination stops.
35. In a tabulating mechanism for type-
writing machines, the combination of a plu-
rality of column stops having contact points
out of line, and means adapted at will to en- 65
gage and arrest a predetermined one of said
plurality of column stops, said means com-
prising a plurality of variably movable de-
nomination stops.
36. In a typewriting machine and in tabu- 70
lating mechanism, the combination of a car-
riage, a set of selectable column stops, de-
nominalional positioning mechanism for co-
operation with said column stops, and means
for operating said denominational position- 75
ing mechanism denominational to deter-
mine the denominational position of arrest,
and variably to select a column.
37. In a typewriting machine and in tabu- 80
lating mechanism, the combination of a car-
riage, a set of selectable column stops, de-
nominalional positioning mechanism for co-
operation with said column stops, and means
for operating said denominational position- 85
ing mechanism variably to select a column
at the same time that said mechanism is oper-
ated to determine the denominational posi-
tion of arrest.
- Signed at the borough of Manhattan, city
of New York, in the county of New York, 90
and State of New York, this 14th day of
October, A. D. 1905.
